CLAIM

The ornamental design for a graphical user interface for a display screen or a portion thereof, as shown and described.

DESCRIPTION

The FIGURE is a front view of a graphical user interface for a display screen or a portion thereof showing the new design. The broken line showing of the display screen and the broken line showings of text and portions of the user interface are for environmental purposes only and form no part of the claimed design.

UNITED STATES PATENT AND TRADEMARK OFFICE
CERTIFICATE OF CORRECTION

PATENT NO. : D685,387 S
APPLICATION NO. : 29/398981
DATED : July 2, 2013
INVENTOR(S) : Sedar Kurtkaya et al.

Page 1 of 1

It is certified that error appears in the above-identified patent and that said Letters Patent is hereby corrected as shown below:

Title Page, Col. 2, below item (74), please insert the following:

-- ACKNOWLEDGEMENT

This invention was made with government support under Grant No. HG003918 awarded by
the National Institutes of Health. The Government has certain rights in the invention. --

Signed and Sealed this
Twentieth Day of August, 2013

Teresa Stanek Rea
Acting Director of the United States Patent and Trademark Office
